UNITED STATES PATENT OFFICE.

MOSES ISAACS, OF NEW YORK, N. Y.

CLOTH-LAYING-UP MACHINE.

Application filed November 20, 1920. Serial No. 425,323.

To all whom it may concern:

Be it known that I, MOSES ISAACS, a citizen of the United States, and a resident of the city of New York, borough of Manhattan, county and State of New York, have invented certain new and useful Improvements in Cloth-Laying-Up Machines, of which the following is a full, clear, and exact description.

10 Among the principal objects which the present invention has in view are: to lay up cloth preparatory to cutting the same to shapes, the cloth being spread alternately from opposite ends of the pile; to save time 15 in the operation; to reduce the manual operations in the preparation of the pile; and to simplify and cheapen the construction of a machine operated for the purposes stated.

Drawings.

20 Figure 1 is a side view of a machine constructed and arranged in accordance with the present invention, said machine being shown as in service.

25 Figure 2 is a similar view of the machine on enlarged scale, the machine being shown as at the end of a lay.

Figure 3 is a detail view on enlarged scale, showing a fragment of the frame of 30 the machine, and means for operatively positioning the detent extraction thereof.

Figure 4 is a detail view partly in section of a fragment of the means for elevating and lowering the extraction, the section being taken as on the line 4—4 in Figure 3.

Description.

Heretofore machines have been employed for laying up cloth wherefrom sections of 40 clothing are to be cut in bulk by means of a power-driven knife or other cutter. These machines have been easily assorbed in two classes, the one class being adapted for laying the cloth from a single piece or bolt, 45 folding the layers at each end of the runway or pile. The other class of machines have been adapted to lay the cloth from one end of the pile only. A characteristic of this class of machines has been the necessity of 50 making a complete return trip of the machine for each ply or lay of cloth.

The present invention provides for handling two separate "pieces" of cloth similarly disposed but arranged to be laid up 55 alternately and from opposite ends of the pile. To this end the present machine is

provided with oppositely disposed guide arms, each having a spreader rod 9 for spreading the cloth. The designating letters A and B and C have been used to distinguish the "pieces" or "bolts" of cloth and the extensions therefrom.

To accommodate the two pieces A and B, the frame 10 has two platforms on which the said pieces are deposited. From each of 60 the platforms the cloth is carried to a stripping roller 11, whence it passes between tension bars 12 and 13, the angular arrangement of which produces a greater or less tension or resistance to the pull of the loose 65 ends 14.

Interposed between the tension bar 13 and the spreader rod 9 are guide rods 15. The stripping rollers 11 for the lower and upper pieces A and B are supported in bearing brackets 16 and 17 respectively. The brackets 16, as seen best in Figure 2 of the drawing, are pendent from the side bars of the upper platform or table, while the brackets 17 are goose-neck extensions from the 75 standing frame 18.

The spreader rods 9 are extended between small extractor plates 19 at opposite sides of the machine. The extractor plates 19 are pivotally mounted on rocking arms 20, and 80 are spaced apart a distance greater than the width of the pile C. The plates 19 are designed to dislodge and carry weighted detent bars 21, which are employed for holding the free end of the cloth, while it is 85 being spread. To this end each of the plates 19 has a forwardly-extending finger 22. The said fingers extend below the detent bars 21 before the vertical edges 23 of said plates engage the said bars to slide the same from 90 the pile of cloth to be thereafter supported on the fingers 22, as seen best in Figure 2 of the drawings.

The plates 19 are held in horizontal position by link arms 24, which are connected 100 by the pins 25 and 26 with the plates 19 and the frame 10 respectively. The outside arms 20 in each pair has a manipulating extension 27. The extension 27 is employed for elevating and lowering the extractor plates 19 and parts connected therewith.

To elevate the end of the arms 20 the extremity of the extension 27 is lowered. To accomplish this the eccentric cams 31 110 are each mounted on pin shafts 32. The pin shafts 32 are provided with a hand

wheel 33, by which the said shafts may be rotated or be withdrawn from and introduced into any of the perforations 34 formed in the frame 10.

5 The shafts 32 extend through a perforation in the end of each of the link arms 35. The link arms 35 are pivotally mounted on shaft 36 which are rigidly connected to the extensions 27.

10 By reference to the drawings it will be seen that if the operator withdraws the pin shaft 32, using for that purpose the hand wheel 33, from any one of the perforations 34, he may move the free end of the link 15 35 to a higher or lower position, and the cam 31 will then rest in the path of the extension 27 at a correspondingly higher or lower position.

15 It will also be seen that within the scope 20 of the movement of the cam 31, the extension 27 may be rocked on the shaft 36, by the cam 31, as the hand wheel 33 is turned by the operator. As the free end of the extension 27 is raised or lowered the extractor plates 19 are correspondingly raised 25 and lowered. In this manner the said plates 19 and the fingers 22 thereof are disposed with reference to the operating-position of the detent bars 21, as the stack C increases 30 in height.

30 The operation of the machine is as follows: Stacks A and B are disposed on their respective platforms or tables on the machine. An end of the cloth A or B is 35 then placed under one of the bars 21. To accommodate the fingers 22 of the plates 19 to permit them to pass under the bars 21, wedge shaped boards 37 are placed on the spreading table beneath the bars 21 and the 40 edges of the first few piles of cloth laid there. The boards 37 are sufficiently thick to permit the introduction of the fingers 22 of the extractor plates 19 under the bar 21 which rests on the said board. The free 45 end of the cloth having been thus arranged, the operator grasps the frame by one of the handles 38 thereof, and carries it to the opposite end of the table or runway on which the machine is operating. The 50 first stretch of cloth is cut at the desired length and the free end is permitted to dangle. The machine is then moved back toward the initial end of the lay until the spreader rod 9 and the free end of 55 the cloth from the other piece is in position to be anchored by one of the detent bars 21 in register with the freshly made end of the first layer of the cloth. As at the opposite end a lifting board is introduced 60 beneath the said freshly cut end of the first ply and the original end of the second ply and the second bar for anchoring the same is placed thereon. The detent having been thus placed in position, the machine 65 is quickly returned to the initial end of the

lay, and is moved beyond the same, until the following spreader bar 9 has passed over the end of the original stretch of cloth.

It will be observed that as the machine has been returned to the initial end of the 70 lay, the fingers 22 of the extractor plates 19 at the forward end of the advancing machine extend below the bar 21, which was holding the first lay of the cloth, and that the vertical walls 23 engage and displace 75 the bar 21 carrying it from the board 37 and the cloth on which it rested, to rest upon the fingers 22 which thereafter carry the bar as the machine is moved.

The second length of the cloth is now 80 severed by any suitable means to register with the end of the first layer of cloth. The operator now turns the hand wheel 33 associated with the plates 19 carrying the weight 21 and rotates the same to force the 85 cam 31 on the free end of the extension 27 which rocks the shaft 36 and elevates the ends of the arms 20 carrying the plates 19. This raises the bar 21 above the level of the top of the cloth. The machine is then 90 returned until the following loose end of the "piece" of the cloth first spread coincides with the ends of the two layers previously disposed on the runway or table. At this point the operator turns the hand wheel 95 33 to remove the cam 31 from the extension 27 which lowers the plates 19 and drops the bar 21 to rest on the newly laid end of cloth.

This series of actions is repeated until 100 with the increasing height of the pile of cloth on the table or runway it becomes necessary to shift the working position of the plates 19 and parts connected therewith. This is accomplished by withdrawing the 105 pin shafts 32 from the perforations 34 in which they have been operating to the next lower perforations. The extension 27 is carried with the shaft 32 and the arms 20 connected therewith are correspondingly 110 lifted so that the working position of the plates 19 connected therewith is disposed as desired.

It is obvious that should it be desired 115 this machine may be employed for laying cloth from a single stack employing to this end only one of the spreader bars 9 and the arms 20 connected therewith. This would require that the machine be returned from what may be called the far end of the lay to 120 the near or initial end of the lay without spreading the cloth, or in other words the cloth would be then spread from one end only.

Claims.

125

1. A machine as characterized comprising a portable frame; a plurality of supports for separate supplies of cloth mounted on said frame; a plurality of guide frames for 130

delivering cloth from said supplies to opposite ends of said frame; a plurality of holding members for retaining said cloth at the free end of each layer thereof; and 5 means carried by said machine for alternately removing and temporarily transporting said holding members from the opposite ends of said cloth to return the same to holding position for the ply thereof next to be laid.

2. A machine as characterized comprising a portable frame; a plurality of supports for separate supplies of cloth on said frame; a plurality of guide frames, each extended 15 from one end of said portable frame for delivering cloth from said supplies in opposite directions from said frame; a plurality of weighted members to rest upon and retain the free end of each ply of cloth while the 20 same is being spread; and means carried by said frames for removing said weighted members from the cloth and from the end thereof toward which the machine is moving, said means embodying a plurality of 25 hook-like members for extending beneath the ends of said weighted members for supporting the same when removed from said cloth.

3. A machine as characterized comprising a portable frame; a plurality of supports for separate supplies of cloth on said frame; a plurality of guide frames, each extended from one end of said portable frame for delivering cloth from said supplies in 35 opposite directions from said frame; a plurality of weighted members to rest upon and retain the free end of each ply of cloth while the same is being spread; means carried by said frames for removing said 40 weighted members from the cloth and from the end thereof toward which the machine is moving, said means embodying a plurality of hook-like members for extending beneath

the ends of said weighted members for supporting the same when removed from said cloth; and means for varying the operative position of said hook-like members in correspondence with the service disposition of 45 said weighted members.

4. A machine as characterized comprising 50 a plurality of spreading frames for successively laying plies of cloth; a plurality of weighted members adapted for disposition on the free end of each ply as the same is spread; and a plurality of supports for said 55 weighted members, one of said supports being carried by each of said frames for removing the said supports from the ply cloth prior to the disposition thereon of the final end of each ply. 60

5. A machine as characterized comprising a plurality of spreading frames for successively laying piles of cloth; a plurality of weighted members adapted for disposition on the free end of each ply as the same is 65 spread; and a plurality of supporting members having extended hooks and pushing shoulders for removing said weighted members from said cloth for disposition upon 70 said hooks to be carried thereby away from said cloth.

6. A machine as characterized comprising a plurality of spreading frames for successively laying piles of cloth; a plurality of weighted members adapted for disposition 75 on the free end of each ply as the same is spread; and a plurality of supporting members having extended hooks and pushing shoulders for removing said weighted members from said cloth for disposition upon 80 said hooks to be carried thereby away from said cloth, to be returned thereby above the free end of the next laid ply for disposition thereon to anchor the same while the said ply is being laid.

MOSES ISAACS.
